COMBINED MOVING COIL LOUDSPEAKER
AND TRANSFORMER

John J. Root, New York, N. Y.

Application October 9, 1946; Serial No. 702,299

5 Claims. (Cl. 179—115.5)

1

This invention relates generally to electro-acoustic transducers and it is more particularly directed to improvements in loud speakers incorporating motors of the magnetic type.

This application is a continuation in part of my prior application Serial No. 679,100, filed June 25, 1946. In that application I disclosed a loud speaker of such principles and design as to be of small size and weight and wherein the overall depth of the speaker was substantially determined by the size of its cone. The instant invention incorporates many of the advantages outlined in said prior application and further adapts its principles to a moving coil type or electrodynamic speaker.

In prior types of moving coil driving unit speakers, the coil was generally disposed at the apex of and behind the cone. Built around the coil and extending further rearwardly was either a housing for a polarizing field coil or a permanent magnet arrangement. An output transformer was generally mounted on the framework in order to match the impedance of the voice coil to the output circuit to which the speaker was connected.

The present invention further makes possible the mounting of the matching transformer so that the overall space requirements of the loud speaker are minimized.

Other objects of my invention will be apparent from the following description, it being understood that the above general statements of the objects of my invention are intended to describe and not limit it in any manner.

Referring to the drawing:

Fig. 1 is a cross sectional view of a loud speaker constructed in accordance with the principles of the invention, and taken across line 2—2 of Fig. 1.

Fig. 2 is a top view thereof.

The speaker assembly comprises a cone diaphragm 10 which may be fabricated of stiff paper or any other non-magnetic material having suitable acoustical properties. Diagram 10 is formed with conventional corrugations 11 and is secured around its periphery 12 to an annular bracket member 13.

Bracket member 13 is connected at spaced points thereof as by screws 14 to an annular casting wall 15 having an integral depending flange 16. Casing wall 15 as well as flange 16 function as a portion of the ferromagnetic circuit and are therefore made of steel or equivalent ferromagnetic substance. The casing further comprises the annular floor 17 formed with an integral reen-

trant column 18 which, in cooperation with flange 16, provides an electromagnetic air gap as will be hereinafter described. Maintained between wall 15 and floor 17 as by bolts, not shown, is an annular permanent magnet 19 for supplying a polarizing field to the unit.

Adjacent to the periphery of diaphragm 10 is connected as by a suitable adhesive an annular, tube-like extension 20 which may be of insulating material. Such connection is effected substantially adjacent to the peripheral portion of the conical area 21 of the diaphragm 10 or, as otherwise stated, adjacent to the periphery or brim of the diaphragm as represented by the edge portion having the corrugations 11. Secured in a conventional manner to the extension 20 is the moving or voice coil 22 so that it is concentric with the axis of the diaphragm and disposed within the electromagnetic air gap produced by the flange 16 and reentrant column 18.

Casing wall 15 and floor 17, as spaced by the permanent magnet 19, define an annular chamber in which is disposed the annular output transformer 23. Transformer 23 comprises a primary winding 24 having leads 25 and 26 and a secondary winding 27 having leads 28 and 29. As is conventional, leads 28 and 29 of the secondary winding are connected to the voice coil 22 which is thereupon provided with audio currents so as to produce a magnetic field. In the instant embodiment such connection is effected through the rivet 30 and lug 31 to which both one voice coil lead and secondary winding lead 29 are soldered. A similar connection for the other voice coil lead is effected through the rivet 32 and soldering lug 33. It will be recognized that the construction of transformer 23 is such as to produce a stepped down secondary winding 27 to match the impedance of the voice coil 22. Transformer leads 25, 26, 28 and 29 may emerge from suitable openings 34 and 35 formed in the floor 17.

To operate the loud speaker from a vacuum tube amplifier, leads 25 and 26 are directly connected to the plate of the final power tube of the amplifier and the positive plate voltage terminal, respectively. In the absence of an audio signal from the power tube, the permanent magnet 19 polarizes flange 16 and column 18 north and south, respectively, so as to establish a constant field in the air gap formed between them. Upon the introduction of an audio signal to the amplifier, an alternating current component corresponding to the signal appears in the output of the power tube. The resultant current which flows through the voice coil 22 produces a mag-

netic field which interacts with the polarizing or constant magnetic field to produce a force which moves the coil parallel to the axis of the diaphragm 10. This produces the required vibration or movement which generates sound waves.

It is to be observed that by driving diaphragm 10 at its peripheral area and by disposing the voice coil thereat, a substantial reduction is made possible in the space occupied by the speaker assembly. This objective is further contributed to by the disposition of the output transformer which, in distinction to conventional dispositions thereof, does not jut out from the main body of the speaker. The magnetic structure of the speaker is built away from the central area of the diaphragm so as to permit the formation of a cone thereat. The magnetic structure and transformer laterally surround the conical area, the depth of the motor assembly being substantially equivalent to the height of the conical central area so that it is disposed in a plane defined by the height of the conical area.

Thus, there has been shown what at present is considered a preferred embodiment of the invention. It will be apparent, however, that many changes and modifications are possible without departing from the spirit thereof. For example, where the power tube of the amplifier is drawing a high value of current, the primary winding 24 may be relied upon to supply a polarizing source as described in my prior above mentioned application. In this event, the permanent magnet 19 would be unnecessary.

I claim:

1. An electroacoustic transducer comprising in combination an acoustical diaphragm having a conical central area, a voice coil mounted adjacent to the periphery of said diaphragm so as to permit said conical central area to vibrate freely, and electromagnetic pole means of annular form disposed in operative relation to said voice coil adjacent the periphery of said diaphragm whereby the apex of said conical area is unobstructed thereby, said electrical pole means forming a chamber, and an annular transformer for supplying audio signals disposed within said chamber and electrically connected to said voice coil.

2. An article according to claim 1 wherein said chamber is of a depth substantially equal to the height of the conical central area and is substantially disposed in a plane defined by said height.

3. An article according to claim 1 including a permanent magnet of annular form for supplying a polarizing force to said voice coil, said permanent magnet being disposed adjacent the periphery of said diaphragm, and substantially in the plane of said chamber.

4. An electroacoustic transducer comprising a combination an acoustical diaphragm having a conical central area, a voice coil mounted adjacent to the periphery of said diaphragm so as to permit said conical central area to vibrate freely, electromagnetic pole means of annular form disposed in operative relation to said voice coil adjacent the periphery of said diaphragm whereby the apex of said conical area is unobstructed thereby, a permanent magnet for supplying a polarizing force to said voice coil, said electromagnetic pole means and permanent magnet forming a chamber laterally surrounding said conical central area, said chamber being of a depth substantially equal to the height of the conical central area so as to be disposed in a plane substantially defined by the height thereof, and an annular transformer for supplying audio signals disposed within said chamber and electrically connected to said voice coil.

5. An electroacoustic transducer comprising in combination an acoustical diaphragm having a central area and a brim integral therewith, an annular extension formed on said diaphragm adjacent said brim, a voice coil wound around said extension so as to be disposed adjacent the periphery of said diaphragm and so as to leave the central area of said diaphragm free to vibrate, electromagnetic pole means of annular form disposed in operative relation to said voice coil adjacent the periphery of said diaphragm so that the apex of said conical central area is unobstructed thereby, a permanent magnet for supplying a polarizing force to said voice coil, said electromagnetic pole means being mutually spaced by said permanent magnet so as to form a chamber therewith, said chamber being of a depth substantially equal to the height of the conical central area, and annular transformer means for supplying audio signals disposed within said chamber and electrically connected to said voice coil.
